UNITED STATES PATENT OFFICE

GEORGE ANDERSON, OF CHICAGO, ILLINOIS

DETACHABLE VENTILATING SHADE BRACKET

Application filed May 29, 1924. Serial No. 716,722.

This invention relates to novel shade bracket for window shade rollers and the like, and more particularly to a detachable ventilating shade bracket which has for its particular object the provision of a bracket for maintaining a window shade in position so that it may be moved up and down with the window, preferably the upper window or sash, to provide for proper and convenient ventilation at the top of the window when the upper sash is lowered, without permitting the shade to blow or flap under the action of air current or wind in such a manner as to mutilate the shade or to injure curtains suspended or hung at the inside of the window, as well as to facilitate window cleaning and the maintenance of the shade in a clean and sanitary condition and avoid the possibility of the shades getting in a condition of disrepair in undue time.

Another object of this invention is the provision of a shade bracket for supporting window shades or the like which shall be mounted directly upon the upper or rearward window sash and which will not interfere with the motion of one sash past the other when it is desired to clean the windows or for any other operation which necessitates the movement of the sashes up and down past each other, and which is so constructed that the contact of the top rail of the lower sash with the bracket will be cushioned in such a manner as to absorb the shock should the lower sash be unduly raised or the upper sash unduly lowered to open the window when the brackets are in position with or without the shade hung therein, and which will also obviate the possibility of the shade being dislodged from the brackets, and particularly at the spindle end of the shade which is usually provided with a rectangular or other polygonal shaped end in cross section which engages a rectangular opening in the bracket to cause the spring to function in winding the shade upon the roller in the usual manner.

Another object of the invention is to provide a novel form of bracket for supporting shade rollers and the like, which may be attached to the upper sash of the window and which will be accommodated in the space be-

tween the parting strip and inner stop of the frame, so as to permit a shade of extra width to be employed, thereby allowing a minimum of space between the edges of the shade and the sides of the frame of the window, especially in connection with modern window frame construction where the mouldings at the inside of the frame as have heretofore been customary, are omitted, while at the same time accommodating the usual sash cord or chain and not in any wise interfering with the movements thereof in raising and lowering the sash.

A still further object of the invention is to provide a novel form of bracket for the rectangular spindle end of the roller which will permit convenient mounting of the roller in the bracket by first inserting the round spindle end of the roller and then inserting the rectangular spindle end in the respective brackets, the bracket having the rectangular opening being constructed in a novel manner and provided with an entrance slot opening at the rear and adjacent to the sash cord, so that the sash cord will close the mouth of the slot over which is provided a top portion or hood designed to guide the rectangular spindle end into the vertical portion of the slot of the bracket but adapted to prevent dislodgement of the roller in an upward direction due to the lower sash striking the roller or otherwise.

A still further object of the invention is to provide a novel bracket including the bracket proper having the rectangular bearing opening for the correspondingly shaped spindle end of the shade roller, in which the spindle engaging portion is offset outwardly from the main portion of the bracket so that a wider and longer shade will be accommodated by the brackets between the sides of the window frame in the space between the parting strip and the inner stop, as heretofore referred to, thus obviating wide openings between the side edges of the curtain or shade and the window frame so that vision into a room is obstructed or prevented from the outside, even at a very sharp angle, owing to the narrow space between the sides of the shade and the sides of the window frame, as com-

pared with the spaces allowed by shades as heretofore hung. The bracket is so constructed at the slot and opening that the entrance and removal of the rectangular 5 spindle into and from the slot will be facilitated, and may be readily accomplished without inconvenience.

A further important object of this invention is the provision of a two-part bracket for 10 window shades or the like which is adapted to have one of its parts readily removed from a window so that the window panes may be cleaned and so that there will be no obstruction to the movement of one of the sashes past 15 the other, said two-part detachable shade bracket being adapted to maintain the shade on its roller in a position upon the upper window sash so that it may be movable with the window, while a deep offset or curved 20 portion between the main portion of the bracket and the bearing portion which is offset outwardly, permits the shade to track or be accommodated therein as it is moved up and down to raise and lower the shade and to 25 wind and unwind the same upon and from the roller without engaging and mutilating the side edges of the shade, and also to serve as a stop to engage the shade slat at the bottom or thickened portion whereby the end of 30 the shade will be prevented from running over the roller and unwinding therefrom when once wound thereon and set or adjusted to a proper position with proper spring tension to cause complete winding of the shade 35 upon the roller.

Other and further important objects of the invention will be apparent from the disclosures in the accompanying drawings and the following specifications.

40 The invention, in a preferred form, is illustrated in the drawings and hereinafter more fully described.

In the drawings:

Fig. 1 is an inside elevation of a window 45 with a pair of co-operating window sashes therein, showing the improved bracket of this invention.

Fig. 2 is a fragmentary sectional elevation 50 partly broken away and showing the brackets applied to the upper sash of the window with the shade and its roller mounted therein, the frame being shown in section.

Fig. 3 is a horizontal sectional view taken on the line 3-3 of Fig. 2.

55 Fig. 4 is a vertical sectional view taken on the line 4-4 of Fig. 2 and showing the action of the top of the lower sash engaging the roller and brackets or effect of upward force being applied to the roller tending to 60 dislodge the spindle ends from the brackets, which is prevented by the present construction.

Fig. 5 is a dis-assembled perspective view of 65 the two part detachable bracket showing the rectangular spindle engaging end, and

Fig. 6 is a face view of the bracket proper illustrated in Fig. 5 and showing the manner of engaging and disengaging the rectangular spindle end of the roller therewith.

Referring to the drawings in detail, in 70 which like reference characters designate corresponding parts throughout the several views, the numeral 7 indicates a window frame having the usual outer stop 8, control stop or parting strip 9 and inner stop or bead 10, between which the grooves or guide-ways 11 and 12 are provided for the upper and lower sashes 13 and 14 respectively, of the window having the usual window panes. The sash cord is designated at 15, and it is understood that the outer sash is set rearward from the inner or lower sash and provision made for clearance between the same at opposite sides of the parting strip 9 in the usual manner, in connection with window frames 75 having the usual inner mouldings or in which such mouldings are provided at the inside wall or where such mouldings or panels are omitted and the same terminate at the inner stop 10, as is well known in modern construction. 80

As shown in the drawings, the improved 85 detachable ventilating shade bracket of my novel invention is applied directly to the face of the upper sash 13, being applied so that 90 the top edge thereof is in line with the top of the glass or window pane and lower edge of the top part of the upper sash. The bracket is made in two parts, one part consisting of a plate 16 adapted to be fixed to the top 95 window sash and held in predetermined position thereon by means of ordinary wood screws or the like. The plate 16 is provided at its top and bottom with bent over lugs or flanges 17 which provide a pair of grooves or slots into which is adapted to ride a corresponding plate 18 which forms an integral 100 part of the detachable bracket member 19. While I have described the bracket as having the plate or angular base portion 18 to engage 105 the grooves of the plate 16, I desire to have it understood that the bracket may be made in one piece and fastened directly to the sash or frame if desired, or otherwise anchored thereto, without departing from the spirit and 110 scope of the invention herein defined and to be subsequently pointed out as claimed, reference being particularly had to the construction of the bracket for accomplishing the objects 115 set forth in the statement of the objects of the invention and the mounting of the rectangular spindle end of the shade roller, although the construction shown and described is the preferred one. As shown more particularly in Fig. 5 of the drawings, an opening or slot 20 is provided in each bracket 19 and 19', the latter being the bracket provided for the round spindle end of the shade roller. The slot 20 is provided in the base portion 18 120 spaced from its inner edge and extends into 125

the bracket proper in angular relation to the plate or base 18, as indicated at 21 at right angles thereto, these parts being formed integral.

- 5 The plate 16 is provided with a plurality of screw holes 22, preferably three in number, one being provided near its inner edge and two in line near its outer edge, the three openings being arranged in substantially triangular relation so that when the plate or base 18 is engaged with the grooves formed by the top and bottom flanges 17, the bracket member or part extending at right angles to the base 18 will ride over the head of a screw 23 10 engaging the inner hole and used for fixing the plate in position on the sash. However, as above set forth and as will be noted from the drawings, since the slot 20 does not extend completely through the plate or base 18, 15 when the bracket is applied to the fixed plate 16 with the edges thereof sliding under the lugs or flanges 17, the inner end of the slot 20 will form a stop to engage the screw 23, so that the position of the bracket will be automatically determined by the contact of the forward end of the slot with the screw which 20 also serves as an anchoring means for the plate and thereby limits the outward displacement of the bracket proper on its fixed 25 mounting member or plate 16. After the shade roller is then applied to the bracket there is no possibility of the roller becoming detached or falling off in use as the pressure against the brackets 19 and 19' acts only in 30 the direction to force the rear end of the slot 20 more firmly against the wood screw or other fastening means which maintain the plate 16 in position.
- In connection with the screws 24 which engage the outer two holes of each plate 16, the brackets 19 and 19' as shown more particularly in Figs. 4 and 5 of the drawings are provided with ribs, and indentations 25 which stiffen the bracket at the bend and accommodate the heads of the screws 24 in case countersunk screws are not employed, also furnishing an additional stop to limit the displacement of the bracket in its mounting. The heads of the screws do not overlie the 40 surface of the base 18 of the slot 20 and this prevents the formation of a leverage tending to lift the screws from their securing position and provides for firmly securing the mounting member 16 to the sash. The screws 45 24 also provide the greatest securing strength near the outer portion of the plate 16 so that should the top of the lower sash or check rail strike the bracket at its bottom edge and corner 26, dislodgement of the fastening 50 means and parts of the brackets will be prevented. Furthermore, owing to the corner portion 26 engaging the comparatively soft wood of the sash as shown in Fig. 4 of the drawings, the impact will be cushioned and 55 shock absorbed owing to the metal of the 60 65

bracket slightly sinking or embedding into the wood, thus relieving the fastening screws of the bracket of unnecessary stresses.

As will be observed from the drawings, and particularly in Figs. 3, 4 and 5, the brackets 19 and 19' are of angular formation in plan, the bracket proper extending substantially at right angles to the securing portion or base plate 18 which latter fits flat against the anchoring member or sash, and after extending perpendicularly from the sash, is offset or bent outwardly at an obtuse angle, substantially at right angles, as indicated at 27 and then forwardly in an obtuse angle, substantially at right angles, as indicated at 28 parallel to the main portion between the parts 18 and 27 but offset outwardly therefrom and then bent inwardly at obtuse angles, substantially at right angles, as indicated at 29 to provide a comparatively deep offset or outwardly curved bend adapted to accommodate the edge of the shade, and in which the latter is adapted to track as it is moved up and down to raise and lower the shade 30 and to wind and unwind the same upon and from the roller 31 without engaging or mutilating the side edges of the shade. Furthermore, the outer portion 32 at the end of the bracket is offset outwardly with relation to the inner portion but is disposed inwardly from the portion 28 and therefore the portion 27 forms a shoulder or serves as a stop to engage the shade slat 33 at the bottom or thickened portion whereby the end of the shade will be prevented from running over the roller and unwinding therefrom when once wound thereon and set or adjusted to a proper position with proper spring tension to cause complete winding of the shade upon the roller. That is, the slat will not be 105 permitted to pass the portion 27 but will be held or wedged between the shade and the bracket at the part 27, as indicated in Fig. 4 of the drawings. This will also prevent the shade from blowing or flapping under the action of air currents entering the room above the upper sash when the latter is lowered for ventilation, in addition to the fact that the shade is attached to the upper sash and lowered therewith so as to be primarily free 110 from being blown, torn or causing any rattling incident to the air currents.

Another important improvement in the bracket and constituting a distinctively novel part of the same, is at the part 32 which is shown substantially circular in face view, in the preferred construction and provided with a vertical slot 34 of substantially rectangular contour, to receive and fit the rectangular spindle end 35 of the shade roller 31. It will be noted that the slot 34 is vertically disposed and instead of being open at the top or front, is open at the rear through the entrance portion or slot 36, the bottom wall of which is 115 formed by the top edge of the bracket proper, 120 125 130

while the front portion is provided with an upward and rearward extension at the top of the outer portion 32, thus providing a slot at the top portion of the bracket entering 5 from the rear on a level with the top edge of the bracket, and providing an overhanging part or hood 37 at the top overlying the vertical slot 34, to prevent the spindle end of the shade from being forced up out of the 10 slot or bearing and thereby preventing displacement of the shade roller from the bracket. The overhanging part or hood 37 may be of any suitable length, that is, its degree of extension rearwardly beyond the vertical portion of the slot and the top edge of the bracket rearwardly of the vertical portion of the slot 34, may be varied, with relation to the sash cord 15 from a point in close proximity to said sash cord to a 15 point alongside of or in rear of the same, thus necessitating that the sash cord be displaced rearwardly when the rectangular spindle end of the roller is inserted into the slot or removed therefrom. In 20 this connection, it is pointed out that the opposite bracket is constructed in the same way except that it is provided with a circular bearing or opening 38 to receive the round spindle end 39 of the shade roller and the bracket 19' is attached to the upper sash in 25 the manner as set forth above.

The corner of the slot at the top edge of the bracket 19 where the entrance portion 36 leads into the vertical portion 34, is rounded 30 off as indicated at 40 to guide and permit the rectangular spindle end of the shade roller to pass into and out of the vertical portion of the slot, which action would not be possible were the corner left square, unless the slot was 35 made unnecessarily wide or otherwise formed for this purpose. However, when the spindle end 35 is in position in the vertical portion of the slot, it will be retained in this position by the vertical portion below the rounded 40 corner 40 in conjunction with the opposite side wall and held from turning during the winding and unwinding of the shade. When the spindle end 35 is moved into and out of slot, it will be turned owing to the 45 rounded portion 40 and guided or permitted to pass from the horizontal portion into the vertical portion and vice versa, by applying upward pressure on the roller and then rearward pressure, or forward pressure and then downward pressure. Thus, 50 when the shade is hung, the round end of the spindle is inserted in the bracket hole 38, preferably after slightly lowering the upper sash, and then the rectangular spindle end is 55 disposed over and rearwardly of the hood 37 constituting the top guard of the slot 34 to prevent displacement of the rectangular spindle end of the roller in an upward direction, and then moved forwardly through the entrance portion 36 and finally turned into the 60

vertical portion 34 as previously explained. Removal of the shade is accomplished by reversing the action just described, which however may be readily and easily accomplished as it is thought will be apparent. From Fig. 3 of the drawings, it will be noted that the outer portion 32 of each bracket is disposed slightly inwardly of the inner face of the beads 10 constituting the inner stop of the window, so that the portion 28 is offset 70 into the groove between the center parting strip 9 and the stop 10, and that the spindle ends of the roller also extend into said grooves or slideways, thus accommodating a shade roller of extra length and a shade of 75 extra width so that the edges will lie in close proximity to the stop 10 and obviate the usual extra wide spaces or gaps between the side edges of the shade and the window frame 80 present with shades as heretofore hung. 85

It will thus be seen that the device thus provided will provide effectively for ventilation of rooms and at the same time afford proper privacy by means of shades which can be drawn down as far as desired but left open 90 at the top. In addition, the length of the bracket is such that the shade will be rolled from the inside and passed over the face of the outer or lower sash without contacting therewith, while also avoiding unnecessarily 95 long brackets. Furthermore, no obstruction will be encountered between the movement of the sashes one past the other, as the top or check-rail of the lower sash will clear the 100 upper sash by removing the shade and brackets when it is desired to move one sash past the other for cleaning purposes, and this will mean that the shade will be removed and dusted off so that its life of usefulness will be lengthened and its condition maintained 105 sanitary and clean. In other words, the top or check-rail of the lower sash will clear and pass by the anchoring member or plate 16 when the brackets proper are removed therefrom by sliding the base portion 18 of the 110 bracket out of the grooves 17, but the brackets can be readily hung by reinserting the base portions into the grooves. Where the brackets are attached directly to the frame or otherwise without rendering the same detachable or constructing the same in two parts as described, so that the base portion or plate 18 forms an anchoring means, the same advantages accrue from the formation of the rectangular spindle receiving part including the 115 slots 34 and 36 and the overhanging hood or guard parts 37. 120

I am aware that many changes may be made on numerous details of construction 125 therein throughout the wide range without departing from the principles of this invention and I therefore do not purpose limiting the patent granted hereon otherwise than as necessitated by the prior art. 130

Having thus described my invention, what I claim is:

1. A support, a grooved slide fixed to said support and having stop projections extending from the face thereof, a shade supporting bracket slidable into said slide and having recesses formed therein to receive said projections and limit said sliding movement.
2. A support, a grooved slide, screws with projecting heads securing said slide to said support, a shade-supporting bracket slidably mounted in said slide and having recesses adapted to receive the heads of said screws whereby said bracket is properly positioned on the slide.
3. A support, a grooved slide, screws securing said slide to said support and having heads projecting from said slide, a shade-supporting bracket slidably mounted in said slide and having spaced recesses to receive the heads of some of said screws and also having a slot to slidably receive another of said screws, the ends of said slot and recesses co-acting with said heads to locate and hold the bracket positioned on said slide.
4. In combination with a window, a pair of plates associated with the window, bracket members having one end of each slidably adjustably secured in said plates for varying the relative distance of said members, a roller curtain pivoted between the free ends of said brackets, and having a curtain stick at its free end, each of said brackets being shaped to form a channel, said channels opening inwardly and said brackets spaced apart to provide clearance for the edge of said curtain in said channels, one wall of each of said channels being spaced to engage the ends of said stick when the curtain is fully rolled and prevent the passage thereof past said brackets.

In testimony whereof I affix my signature.
GEORGE ANDERSON.
